UNITED STATES PATENT OFFICE.

RICHARD SYBENGA, OF PELLA, IOWA.

TROUSERS-HANGER.

1,027,223.

Specification of Letters Patent. Patented May 21, 1912.

Application filed March 16, 1910. Serial No. 549,731.

To all whom it may concern:

Be it known that I, RICHARD SYBENGA, a citizen of the United States, and resident of Pella, in the county of Marion and State of Iowa, have invented a certain new and useful Trousers-Hanger, of which the following is a specification.

The object of my invention is to provide a trouser hanger of simple, durable and inexpensive construction designed to support a pair of trousers or the like in such a position that they will be without fold and may be contained within a comparatively small space, and also so arranged as to form creases or folds therein at the front and back of the leg portions and to remove the baggy effect in the trousers caused by wearing.

A further object is to provide a device of this kind capable of supporting one or more pairs of trousers.

A further object is to provide a device of this kind on which one or more pairs of trousers may be readily, quickly and easily placed or removed.

My invention consists in certain details, in the construction, arrangement and combination of the various parts of the device, whereby the objects contemplated are attained, as hereinafter more fully set forth, pointed out in my claim and illustrated in the accompanying drawings, in which:

Figure 1 shows a sectional view of a device embodying my invention, the dotted lines show the position of the spring holder when elevated to receive a pair of trousers. Fig. 2 shows a sectional view on the line 2-2 of Fig. 1, and Fig. 3 shows a side elevation of my improved trouser hanger with a portion of a pair of trousers thereon.

Referring to the accompanying drawings, I have used the reference numeral 10 to indicate the body portion of the trouser hanger which consists of a straight, round piece of material such as wood of a length slightly greater than the maximum width of the trouser legs to be placed thereon. I have provided in the body portion 10 a longitudinal opening extending from one end to a point past its center. The remainder of the hanger comprises a single piece of spring rod comprising a straight portion 11 at one end designed to be inserted in the opening of the body portion 10. At one end of the part 11 is a right angle extension 12 and at the end of the part 12 is an inclined portion 13 extended substantially parallel with the

part 11 to a point adjacent to the end of the part 11. The said part 13 however inclines in a direction from the end of the part 11 as clearly shown in Fig. 1. At the end of the part 13 is an upright portion 14 having at its top a hook 15 designed to receive a nail or other support through which the trouser hanger may be suspended. The resiliency of the spring metal provides for yieldingly holding the inner end of the part 13 in engagement with the central portion of the round body portion 10.

In practical use, I first fold a pair of trousers so that the legs thereof crease at the front and back and I then place the legs of the trousers over the body portion 10 so that the trousers will hang on said body portion at about the knee portions of the trousers. I then place the end of the part 11 in the opening in the body portion 10 and move the spring rod to the position shown in Fig. 3. This can be done readily and easily by springing the part 13 away from the trousers. After the rod has been placed in position in the body portion 10, the resiliency of the spring rod will yieldingly hold the inner end of the part 13 against the trousers. This will tend to hold the trousers firmly to the body portion 10. Obviously several pairs of trousers may readily and easily be supported on the same hanger and it is also obvious that trousers may be very quickly and easily placed in position on the hanger. When it is desired to remove the trousers the operator simply slides the rod within the body portion 10 which obviously may be done very quickly and easily. It is also obvious that trousers supported for any length of time upon the hanger will have creases formed therein at about the knee portions of the trousers on account of them lying flat against the round body portion and it is obvious further that the baggy effect caused by the wearing of trousers will be removed when they are supported on my improved hanger.

One of the advantages of my invention is that trousers may be placed on a wooden roller with the greatest of ease and they may be very quickly spread out smoothly upon the roller, so that they will hang over the roller at the creases thereof. This is largely due to the fact that the roller is removable from the supporting and clamping wire, and the placing of trousers on the roller, or the removal of them from the

roller is always done when the roller is removed from the supporting and clamping device, then after the trousers are in proper position on the roller, the operator need only 5 insert one end of the spring in the opening, in the end of the roller. When he does this, he grasps the end of the roller opposite from the opening, and also the handle of the wire. This enables him to readily spring 10 the central portion of the wire away from the roller, and the clamping portion of the wire will not rub against or tend to wrinkle or crease the trousers, while the parts are being put together when the supporting and 15 clamping device is in position, the operator releases his hand from the roller and upon the clamping portion springs against the trousers and holds the trousers in position and prevents them from rolling and it also 20 prevents the roller from sliding lengthwise.

I claim as my invention:

An improved trouser hanger, comprising a round bar, having a central longitudinal

opening therein, and a spring metal rod having a straight end capable of being readily and easily inserted in and removed from said opening, so that the rod and said bar may be removed for placing trousers thereon, said spring rod also being provided with a body portion shaped to yieldingly engage the central portion of the bar and also provided with a hook to form a support for the hanger, said parts being so arranged that after trousers are placed on the bar and the spring rod is inserted in the bar, 25 its central portion will yieldingly engage the trousers and press them against the bar to hold trousers to the bar and to hold the bar against both rotary and longitudinal movement relative to the rod.

Des Moines, Iowa, Jan. 13, 1910.

RICHARD SYBENGA.
